CLAIM

The ornamental design for a cabin log, as shown and described.

DESCRIPTION

FIG. 1 is a front, top and left side perspective view of a cabin log according to the invention;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The cabin log is shown with two symbolic breaks in its length. The appearance of any portion of the article between the break lines forms no part of the claimed design.
